UNITED STATES PATENT OFFICE.

HORACE E. RICE, DECEASED, LATE OF PHILADELPHIA, PENNSYLVANIA; BY KATHLEEN F. RICE, ADMINISTRATRIX, OF ENFIELD, CONNECTICUT.

IGNITION APPARATUS.

Original application filed November 12, 1920, Serial No. 423,633. Divided and this application filed August 20, 1923. Serial No. 658,247.

To all whom it may concern:

Be it known that HORACE E. RICE, a citizen of the United States, deceased, formerly of the city and county of Philadelphia, State 5 of Pennsylvania, during his lifetime invented certain new and useful Improvements in Ignition Apparatus, and that I, KATHLEEN F. RICE, administratrix of the estate of the said HORACE E. RICE, deceased, do hereby 10 declare to the best of my knowledge and belief that the following specification, taken in connection with the drawings furnished and forming a part of the same, is a clear, true, and complete description of said improvement.

The invention relates to apparatus for controlling the electrical ignition of internal combustion engines, and resides more particularly in distributor structure, features of 20 arrangement and combination of the induction coil structure with the distributor and current controlling structure, and in other features of construction, arrangement and combination hereinafter described and 25 claimed.

This application is a division from application Serial No. 423,633, filed November 12, 1920.

For an understanding of the invention 30 and for an illustration of one of the various forms it may take, reference is to be had to the accompanying drawings, in which:

Fig. 1 is a diagrammatic view of the interrupter or timer structure and associated 35 circuits.

Fig. 2 is a diagrammatic view illustrating motor cylinders or groups of cylinders disposed at an angle with respect to each other.

Fig. 3 is a plan view of part of the apparatus.

Fig. 4 is a vertical sectional view, some parts in elevation, taken on the line 4-4 of Fig. 3, and through structure additional to that shown in Fig. 3.

Fig. 5 is a plan view of part of the structure shown in Fig. 4.

Referring to Fig. 1, alternate spark plugs *p* are those of the six cylinders of one group, and are connected to the stationary distributor terminals *t*; while the plugs *pl*, connected to the stationary distributor terminals *tl*, are those of another group of six cylinders, the two groups forming a twin six engine.

Ordinarily the two groups are so arranged

that between their cylinder axes there is an 55 angle of 60 degrees. In some cases, however, as indicated in Fig. 2, the two cylinder groups *C* and *Cl* are so disposed that the angle between the cylinder axes is 45 degrees. Such is the case in the Liberty twin six motor hereinbefore referred to.

In consequence, when cylinder firing takes place alternately in the different groups, the angular distance between a distributor terminal *t* and the succeeding terminal *tl* is 22½ degrees, while the angle between each distributor terminal *tl* and the succeeding terminal *t* is 37½ degrees, as indicated in Fig. 1, when the rotary distributor arm *D* rotates at half engine speed.

The distributor arm *D* is connected to one terminal of the high tension secondary winding *S* of an induction coil *I* whose primary *P* is connected in the primary circuit extending from the ground or frame *G* through battery *B*, switch *s*, binding post *a*, the aforesaid primary coil *P*, binding post *b* to the interrupters or timers *A* and *B*, both shunted by the condenser *K*, to ground or frame *G*.

The interrupter mechanisms *A* and *B* are 80 shown to be similar in structure, though such similarity is not essential. In the example illustrated they are of the open circuit type, an example of which is described in Kent's Patent No. 1,246,818, though it will be understood that my invention comprehends also the employment of closed circuit interrupters such as illustrated, for example, in Kent's Patent No. 1,289,036. As illustrated, 85 each interrupter comprises the stationary interrupter contact *1* which is momentarily engaged by the cooperating moving contact *2* carried by the yieldingly mounted member *3*, with which is associated the hooked member *4* actuated by the intermediate or hammer member *5*, pivoted at 6 and in turn actuated by the member or lifter *7* controlled by spring *8* and actuated by cam *9*, rotated by and at half speed with respect to the main crank shaft of the motor.

The cam *9* has its control teeth, points or faces, uniformly spaced circumferentially, whereby for each sixth of a revolution of the cam *9*, the interrupter contacts *1* and *2* of one of the interrupters engage and separate and produce a spark. Similarly, in the other interrupter the contacts *1* and *2* engage and separate for each sixth revolution of the cam

9, similarly producing a spark, but the sparks produced by one interrupter, as A, alternate with those produced by the other interrupter, as B. In other words, the 5 interrupter A may produce sparks for all the cylinders of one group, while B produced the sparks for all the cylinders of the other group. While the sparks in the two groups alternate, they do not occur at uniform intervals, as above stated. To insure that they 10 occur at the proper intervals or instants the interrupters A and B are unsymmetrically placed as regards angular position about the cam 9, whereby the interrupter A is operated, and upon further rotation of $22\frac{1}{2}$ degrees by cam 9 the interrupter B is actuated; thereafter the cam 9 rotates $37\frac{1}{2}$ degrees further before again actuating the interrupter A. The interrupters A and B are not 15 opposite each other or displaced by 180 degrees, but by 180 degrees less $22\frac{1}{2}$ degrees.

Accordingly, notwithstanding the fact 20 that the cam points are uniformly spaced, ignition sparks are produced at unequal intervals; and further, notwithstanding the fact that the cam has a certain number of points, six in the example illustrated, there are produced for each revolution of the cam twice as many sparks as there are cam 25 points.

It will be understood, however, that in 30 case sparking at uniform intervals is desired, the same cam and interrupters may be employed. Again assuming a twin six motor, but with the groups at 60 degrees with respect to each other, the interrupters would be placed, for example, 180 degrees less 30 degrees, or 150 degrees from each other. In any event, after actuating one 35 interrupter the cam will be rotated 30 degrees and then operate the other, and so on in succession.

As an example of a structure embodying 40 my invention, reference is now had to Figs. 45 3 to 5 inclusive, wherein 10 is a base or support upon which is the flange 11 having slots 11^a through which may extend bolts or other means for fastening the base 10 upon the framework of the engine or other 45 suitable support, the slots 11^a allowing circumferential adjustment of the base 10 before finally securing it. At its one end the base 10 has the inwardly turned flange 12 in which are the circumferentially extending slots 13, Fig. 5, through which extend 50 screws or bolts 14, each carrying on its lower end the nut 15 between which and the underside of the flange 12 is disposed a spring 16 surrounding the bolt 14, whereby the casing 17, having flange 18 bearing upon flange 12, is resiliently held to the base member 10, the slots 13 allowing rotation of the casing 17 through suitable angle for purposes of 55 advancing or retarding ignition. Upon the bottom of the casing 17 is the bearing sleeve 60

19 within which is the bearing bushing 20 in which rotates the shaft 21 carrying a collar 22 and 23, which detachably connects with a shaft driven by the engine or motor at half the speed of the main crank shaft 70 of the motor, assuming the latter to be of the type employing four strokes per cycle.

Within the casing 17 there is secured to the shaft 21 the governor plate 24, to which are secured springs 25 connected to governor arms 26 pivoted to the plate 24 at 27 and actuating under the influence of centrifugal force the cam carrying plate 28 to move the same angularly with respect to the shaft 21. Secured to the plate 28 is the 80 cam member 9 through which freely extends the distributor shaft 29 concentric with and secured to or integral with the shaft 21.

Covering the casing 17 is the metal plate 30, upon which are mounted the interrupters A and B, a lug or lever arm 30^a serving to rotate the plate 30 and the interrupters with respect to the cam 9 for advance or retardation of ignition. Through the plate 30 extends the aforesaid cam member 9 and through it the distributor shaft 29, whose upper end terminates in the semicircular portion 31 which with part of the circumferentially complete shaft 29 extends into the detachable or removable distributor block 32 of insulating material, having the central boss 33 extending through an aperture in the metallic distributor member D having the rearwardly extending balancing portion d. The distributor D is secured to block 32 by screw 34, threaded into an insert 35 molded in the block 32. Secured under the head of the screw 34 in contact with the distributor D is the bowed spring contact 36 whose free end engages the part d of the distributor.

The member 37 of insulating material, preferably molded, forms a housing for the distributor and for the interrupter mechanisms A and B, whose parts are mounted 110 within the casing 37 on the upper face of the plate 30, in cooperative relation with the cam 9, as hereinbefore described.

In the bottoms of depressions 38 in the upper edge of the casing member 37 and extending to the inner wall or face thereof are secured the inwardly projecting distributor terminals t and t^l hereinbefore referred to, the outer end of the distributor D passing closely adjacent the inner ends of these distributor terminals, whereby the high tension energy from the secondary S leaps the small gaps between the distributor D and the terminals t and t^l in passage to the spark plugs. The connections from the spark plugs to the distributor terminals extend into the apertures 39 terminating in smaller apertures through which the conductors themselves extend into contact with the distributor terminals, to which they may 120 125 130

be soldered or otherwise secured. Upon the upper edge of the casing member 37 is disposed the rubber or other gasket 40, and upon it rests the lower flange 41 of the housing or casing 42, preferably of insulating material, within which is housed the induction coil I which, if suitable or desirable, may be molded directly in insulating material forming the casing 42. Forming the bottom of the casing 42 is the plate 43, preferably of insulating material, carrying the axial contact 44, with which engages the aforementioned distributor contact 36 and connected to yielding contact 45 adapted to engage and contact with the terminal 46 constituting one terminal, as 47, Fig. 1, of the high tension secondary S of the induction coil I, the other terminal of the secondary S being connected to the primary P whose terminals connect, as previously stated, to the binding posts *a* and *b*, comprised in part of the bolts 48 and 49 serving to clamp the casing 42 to the casing 37. Connection to switch *s*, Fig. 1, is made by conductor held under binding post *a*, Fig. 4. The bolt 49 serves also to form electrical connection between one terminal of the primary P of the induction coil and the conductor 50, which is clamped by screw 51 in contact with the condenser housing plate 52 secured upon the top face of the plate 30 by screws 53, the plate 52 being, however, insulated from plate 30, which latter is grounded or connected to the frame by metallic communication through casings 17 and 10 and flange 11, whereby the movable contact 2 of interrupter A and stationary contact 1 of interrupter B, secured to and connecting with the plate 30, are grounded.

Between the plate 52 and plate 30 is held the aforementioned condenser K, whose one terminal connects with the insulated cover plate 52. The stationary contact 1 of the interrupter A is supported by the lug 54 upon the condenser cover plate 52; similarly, the movable contact 2 of the interrupter B connects through its resilient support 3 with the condenser cover 52, upon which said member 3 is secured and with which it electrically connects. Accordingly the condenser cover 52 and one terminal of the condenser, together with the stationary contact of one interrupter and the movable contact of the other interrupter, are connected through conductor 50 and binding post *b* with one terminal of a primary P of the induction coil I.

While, as hereinbefore stated, other types of interrupters than the open circuit type disclosed may be employed, there is a preference for the open circuit type, particularly when of the structure herein disclosed, in that back firing or premature ignition of the motor cannot occur, and in that auxiliary apparatus for preventing back firing need not be provided. In the example illustrated, rotation of the cam 9 in direction opposite to that indicated by the arrow, for a part of a revolution or more, will not, because of the structure and relation of the members 5 and 7, cause engagement and separation of the interrupter contacts essential to production of igniting sparks.

What I claim is:

1. Ignition apparatus comprising a base, a governor chamber thereon, a governor in said chamber, a second chamber adjacent said governor chamber, interrupter mechanism in said second chamber, a casing on said second chamber, and an induction coil in said casing.

2. Ignition apparatus comprising a base, a governor chamber thereon, a governor in said chamber, a second chamber adjacent said governor chamber, interrupter and distributor mechanism in said second chamber, a casing on said second chamber, and an induction coil in said casing.

3. Ignition apparatus comprising a base, a governor chamber thereon, a governor in said chamber, a second chamber adjacent said governor chamber, interrupter mechanism in said second chamber, a casing on said second chamber, and an induction coil in said casing, said second chamber and said casing being rotatable with respect to said first named chamber for advancing or retarding ignition.

4. Ignition apparatus comprising a base, a governor chamber thereon, a second chamber adjacent said governor chamber, a shaft extending into said governor chamber, a governor in said governor chamber driven by said shaft, a casing on said second chamber, an induction coil in said casing, and interrupter mechanism in said second chamber controlling a circuit of said induction coil and driven by said shaft through said governor.

In testimony whereof I have hereunto affixed my signature this 16th day of August 1923.

KATHLEEN F. RICE,
Administrator of Horace E. Rice, deceased.
